(57) **CLAIM**

The ornamental design for a lid of container for kimchi, as shown and described.

DESCRIPTION

1. Lid of container for kimchi

1.1 : Perspective

1.2 : Front

1.3 : Left

1.4 : Top

1.5 : Bottom

1.6 : Perspective view 2

1.7 : Reference view

1.8 : Reference view 2

1.9 : Reference view 3

Reproduction 1.1 is a front perspective view of the lid of container for kimchi; reproduction 1.2 is a front view thereof where the back view is a mirror image; reproduction 1.3 is a left view thereof where the right view is a mirror image; reproduction 1.4 is a top view thereof; reproduction 1.5 is a bottom perspective view thereof; reproduction 1.6 is a bottom perspective view thereof; reproduction 1.7 is a reference view thereof showing a state of being coupled to a container and form no part of the claimed design; reproduction 1.8 is a reference view thereof showing the opened state in which only one side of the fastening part is released and form no part of the claimed design; reproduction 1.9 is a reference view thereof showing the completely opened state in which both sides of fastening parts are released and form no part of the claimed design; this design is for a lid of container for kimchi with hinge structure fastening parts, which can be used by releasing only one side of fastening part; the upper part is made of transparent glass.
